(57) **CLAIM**

The ornamental design for a touch screen pen, as shown and described.

DESCRIPTION

FIG. 1 is a front perspective view of a touch screen pen, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view of the touch screen pen shown in a position of use. The broken lines in the drawings illustrate the portions of the touch screen pen, which form no part of the claimed design.
